UNITED STATES PATENT OFFICE.

FRED I. JUDSON, OF HOUSTON, TEXAS.

AEROPLANE.

No. 888,618.

Specification of Letters Patent.

Patented May 26, 1908.

Application filed January 3, 1908. Serial No. 409,108.

To all whom it may concern:

Be it known that I, FRED I. JUDSON, residing at Houston, in the county of Harris and State of Texas, have invented a new and Improved Aeroplane, of which the following is a specification:

My invention, which relates to air ships of the aeroplane or gliding type, primarily has for its object to utilize the principles of the aeroplane combined with centrifugal blowers capable of being so manipulated and controlled that aerial navigation is rendered practicable and safe.

My invention, in its generic nature, comprehends an improved coöperative arrangement of glider or poiser frame, means mounted thereon for creating a partial vacuum above the said frame by drawing the air down below the frame in such manner that the frame is steadied and held to the upright position and for forcing the air in a smooth current on the under side of the glider or poiser frame, the said air controlling means acting to partially compress the air as it is drawn below the glider or poiser frame, and discharging the same so its expansive power acts on the under side of the poiser or glider sufficiently to exert the required pressure for lifting, the efficiency of the air controlling means depending on the size of said means relatively to the weight of the entire machine.

My invention also comprehends, in connection with a glider or poiser frame, means mounted thereon for creating a reduction of the air pressure above the said frame by drawing the air down and discharging it in a compressed state to expand under the poiser or glider frame, supplemental air controlling means in the nature of rotary propellers located forwardly of the other air controlling means that coöperate with the said other air controlling means to effect a great advantage of operation and result by drawing in and directing rearwardly air from in front of the machine to the said other air controlling means that effect a partial vacuum above the poiser or glider frame, and compressing the air and directing it so it expands under the poiser, and in a direction toward the tail end of the machine.

In its more complete nature, my invention embodies, in connection with the glider or poiser frame, the air controlling means that

effects the partial vacuum above the poiser frame, compresses the air and then discharges it to expand under the said poiser frame, and in a direction rearwardly, a series of side planes or wings controllable from the operator's cage or saddle, whereby the direction up or down or level of the machine may be conveniently and positively controlled, and its still more subordinate features my invention consists in certain details of construction and novel combinations of parts, all of which will be hereinafter fully described, specifically pointed out in the appended claims, and illustrated in the accompanying drawings, in which:—

Figure 1, is a perspective view of a preferred construction of my machine, the same being shown with a pair of propellers on the front and three sets of wing vanes or blades. Fig. 2, is a longitudinal section of the same. Fig. 3, is a side elevation of a modified form of my invention, showing the front air disturbers or propellers omitted, and but two sets of side blades or wings. Fig. 4, is a similar view, the blades or wings being adjusted for causing the machine to descend. Fig. 5, is a diagrammatic plan view that shows the correlative arrangement of the main or poiser frame, the centrifugal blowers and the side wings or blades, and the propellers. Fig. 6, is a diagrammatic side elevation of the poiser or main frame with one set of side wings composed of three vanes or blades, their correlative position Fig. 7, is a side elevation of the form shown in Fig. 5. Fig. 8, is a diagrammatic elevation showing two sets of blowers in use. Fig. 9, is a diagram of one of the blowers and its casing. Fig. 10, is a longitudinal section taken on the line 10—10 of Fig. 2.

In the practical application of my invention, I have provided a main or poiser frame constructed of suitable material and comprising a rigid member 1 that forms the top of a shallow casing 2, closed at the front by the downwardly and rearwardly inclined end 3, at the sides by shallow members 4—4 that extend some distance to the rear of the top 1, and at the bottom by the solid cross member 5.

In the preferred construction, the casing has two independent and transversely disposed compartments 6—6 hereinafter termed "drums" that are formed by the vertical par-

tion members 60—60 that are bent to form a semi-circular front wall and rearwardly extended parallel side walls as diagrammatically illustrated by Fig. 10 of the drawings, 5 it being understood that the top and bottom portions of the drums are formed by the top and bottom members of the casing proper.

Each drum has a central opening 61 that 10 form the air intakes since the air is drawn into the said openings and then discharged rearwardly through the wide outlet mouth 62 of the drum as indicated by the arrows on the drawings.

Within each drum is mounted a centrifugal blower 7 which has the shape of the ordinary blast furnace blowers, the blades having 15 no pitch.

The blower shafts 71 are journaled at their upper ends in a cross brace 10^a on the top 20 member 1 and have bearings in a solid cross member 5 that forms the under side of the casing bottom.

The two blowers are driven to rotate toward each other and for such purpose their 25 lower ends carry chain gears, around which drive chains run, and these are driven from other sprockets 72 on the drive shafts 14 of the motor mechanism, designated X suitably supported on the pendent cage or frame 30 shown in Fig. 1.

9 and 10 designate additional cross members secured on the top 1, one of which 9 has its ends extended beyond the sides of the frame for a purpose presently explained, and 35 81 designates a cross member near the casing and of the top to which the inner ends of the longitudinal slats or strips 50 are attached.

The slats 50 are of light material, bamboo, for example, to the under side of all of which 40 is secured a thin canvas covering 51 and the said slats are made tapering from the inner to the outer ends, whereby the said outer ends are rendered very flexible so that the resistance of the air currents is thereby gradually reduced as the currents pass backward 45 and from beneath the covering 51 to make it easier for directing the machine in ascending.

75 designates a cross brace member secured to the rear ends of the slats 50.

50 8 designates another cross brace, also secured to the slats 50 at about midway the cross members 75 and 81, and the ends of the said brace 8 are extended for supporting the side wings or blades hereinafter fully explained.

In the simplest form of my invention, the wing or side blade mechanisms may each consist of but a single member as shown in Fig. 3, but I prefer to form each set of such mechanisms of three wings or blades disposed one above the other in horizontal planes and projected progressively forwardly from the bottom to the top, as shown in Figs. 1 and 2.

The cross brace 9 that is disposed forwardly of the centrifugal blowers also car-

ries a blade or wing mechanism at each end, arranged similarly to the mechanisms on the ends of the cross brace 8.

All of the several sets of wing mechanisms have their blades or wing members pivotally mounted on their supporting members so they can be readily tipped and so hung that the greatest portion is to the rear of their fulcrums, so that when said wings are released, in the manner presently explained, 75 the rear of the said planes will be tipped up by the air pressure beneath, whereby to direct the machine downwardly, it being understood that by raising the front ends of the wings which is done by suitable levers and 80 cords, also presently again referred to, the machine will be directed upwardly, the main body or poiser frame at all times however remaining on a level or horizontal plane.

Each one of the blade or wing mechanisms is constructed of a light flexible material of suitable strength, and consists of the longitudinal slats 21 that are joined at their front end to a cross piece 22, the several slats 21 being tapering so their rear ends 90 readily bend upwardly and carry the canvas body 23 secured to the under side of the slatted frame.

For making a firm support, the several slats have bearings 24 on the upper ends for 95 receiving the fulcrum bars, as best shown in Figs. 2 and 5, by reference to which it will be seen that to the cross bar 8 that extends laterally from the top of the slatted frame and to another cross bar 10 that extends from the 100 underside of the rearwardly extended bottom member of the main frame or casing, is connected a pair of diagonally and forwardly inclined side bars 84 in which are fulcrumed bars 85—86—87 that carry the several vanes 105 or wings, as shown.

It is understood that all of the several sets of wings or side blade mechanisms are constructed similar to the set above disclosed and shown in Fig. 5.

For manipulating the side wing or blade mechanisms in unison, cords 23^a are secured to the front ends of the uppermost ones of a set of vanes or wings and are passed onto reels 22^a adjacent the seat for convenient 115 operation of the vanes. The several vanes or wings in each set may be joined by a light rod or bar so as to cause all to rock together on their fulcrums, when the front ends are raised by the operator, or when their rear ends drop back by gravity.

12 designates a tank formed within the casing in advance of and between the front ends of the blower drums for storing the gasoline for the motor engine that is carried on 125 the pendent or operator sustaining cage or frame.

So far as described, the manner in which my aeroplane or flying machine operates and its advantages, is best explained as follows: 130

In starting the glide of the machine, the motor is put in operation, which gives the desired speed to the centrifugal blowers. These at once cause an air disturbance of such character that the atmospheric pressure is changed, in such manner as to create a partial vacuum above the machine, and by reason of the increased expansive force of the atmosphere below the poiser or main frame the machine is floated with the poiser always in the horizontal plane, it rising or falling in accordance with the positioning of the vanes or wings at the side.

By reason of mounting the blowers within a shallow casing closed at the front, with drums located therein, having exits that discharge in a direction rearwardly of the machine, and having means for restricting the air that is drawn down through the top so it first becomes partially compressed and then expands upwardly against the flexible and light back or slat frame, I am enabled to obtain ample means for maintaining a balance in aeroplane flight, with a lifting power limited only by the size of the machine and the character of the motor mechanism for lifting.

By arranging the blower drums in the casting end of the frame as shown and described, and extending the side pieces and the bottom of the casing beyond the discharge mouth of drums, an advantageous result is obtained, since the machine gets the full benefit of the expansion of the previously partially compressed air drawn into the drums as it discharges in a rearward thrust from the drum in a laterally restricted condition against the light slatted top frame, its final discharge or expansion being upwardly against the flexible end of the said frame.

It is the currents of air that are drawn down through the drum openings partially compressed and allowed to expand as the currents are directed rearwardly under the slatted frame that causes the poiser frame to remain at a horizontal plane at all times during the operation of the blowers.

The lateral wings, which also exert a sustaining power at the same time are used for guiding the machine to an upper or a lower or lateral position, as desired, since lateral movement may be provided for by properly adjusting the wings at one side or the other, or the several wings at both sides.

Various modifications of the side vanes or wings might be used for accomplishing their desired results, but I prefer to sustain the wings with their largest area or plane at the rear of their fulcrums and with the rear portions flexible, as shown and described, for by hanging the wings, the pressure of and the resistance of the air currents from below is such that the pressure against the vanes or wings is as indicated by the arrows *a* on Fig. 4 which causes the machine to lower, but

when pulled to the position shown in Fig. 8, the air pressure on the under side of the vanes is increased and thereby causes the machine to rise, it being manifest that by adjusting the vanes at one side, more or less that at the other sides the machine will be caused to move laterally as it ascends or descends.

In the drawings, I have illustrated a general arrangement of aeroplane constructed in accordance with my invention, but no particular proportions or sizes of the different parts have been specified, since the said proportions and sizes must depend on the amount of weight to be carried and the capacity of the blowers, and furthermore, I have made no special mention of the hanging frame or car for sustaining the operator, the motor or drive mechanism and the devices for controlling the adjustment of the side vanes or wings, as these in practice, are also arranged to suit the size and lifting capacity of the machine, it being understood, however, that the said pendent or hanging frame is made of the lightest material possible that will stand the required strain.

The opposite edges of the discharge mouths of the drums in which the blowers operate are curved inwardly as at $3^{\times}$ to form checks for preventing the ends of the blower blades drawing the air back into the drums.

From the foregoing, taken in connection with the drawings the operation, construction and the advantages of my invention is believed to be apparent to those skilled in the art to which my invention relates.

An essential feature of my invention lies in the peculiar formation of the casing on the main frame, having its front end constructed to form the least resistance possible in cutting through the air, the manner in which the blowers are arranged for sucking the air into the casing drums, whereby to create the desired change of atmospheric equilibrium, the means whereby the air is but partially compressed and is restricted in its lateral expansion until it has been directed under its substantially maximum force rearwardly and against the under side of the tail end of a frame of gradually increasing flexibility.

The air in my form of machine is drawn into the drums in smooth and steady currents and leaves the drums in a straight rearwardly directed swift current and hence churning of the air is avoided.

It should be again stated that the sides and bottom extensions of the main casing form important elements of my invention, for did the air currents discharge directly from the drums back to atmosphere there would be little or no forward thrust of the machine, but as the air is confined by the said side and bottom extensions in expanding it imparts the desired forward thrust as also the upward pressure, and the flexible top 5 acting somewhat like a bird's tail, ma-

terially aids in providing the proper poise or equilibrium of the machine.

Having thus described my invention, what I claim and desire to secure by Letters Patent, is:

1. In an aeroplane, in combination with a poiser frame having a rear portion of gradually increasing flexibility; of means for drawing air from above the frame for creating a partial vacuum above it and directing the air so drawn beneath the under side of the frame and discharging it over the rear end of such frame.
2. In an aeroplane, a poiser frame, means mounted at the front end thereof for drawing the air down through the frame and other means on the said frame for partially compressing the air thus drawn and directing it rearwardly beneath the under side of the frame and to discharge over the rear end thereof.
3. In a flying machine of the character described, a poiser frame, a car suspended therefrom, a motor on the car, a vertically disposed propeller mounted in the front end of the poiser frame, horizontally disposed propellers mounted on the poiser frame for drawing air from above to below the frame, means for directing the air thus drawn rearwardly, said poiser frame including adjustable side wings, coupling means for joining the motor with the several propellers and means operable from the car for adjusting the side wings of the poiser frame.
4. An air ship, comprising a main poiser frame, wings projected laterally therefrom, each comprising one or more horizontal planes, a car pendent from the poiser frame, a motor thereon, a horizontal propeller mounted on the poiser frame for drawing air down through said frame and actuated by the motor, and means for tilting the horizontal planes of the wings in a vertical direction with respect to the poiser frame, as set forth.
5. In an air ship, a main poiser frame, supplemental poiser members that project laterally from the main frame and are supported to tilt in the vertical direction, said supplemental poiser members being disposed in different horizontal planes and progressively in advance of each other, a car pendent from the main frame, a motor on the car, a pair of horizontally disposed propellers, rotatable toward each other and mounted on the poiser frame to draw air down through the said frame, said propellers being actuated by the motor and means operable from the car for tilting the supplemental poiser members, as set forth.
6. In an aeroplane, a poiser frame, a propeller mounted on the front end thereof for directing the air rearwardly over the poiser frame, means on the poiser frame for drawing the air directly rearward from above to

below the frame and discharge it rearwardly under the frame another frame pendent from the poiser frame, a motor mounted on the pendent frame and drive mechanism coupled with the motor, the propeller and the means for drawing the rearwardly directed air under the poiser frame.

7. In an aeroplane, the combination with the poiser frame, means for sustaining it in its flight, and the pendent or car frame; of means for guiding the direction of the said poiser frame, comprising wings projected laterally from the poiser frame, consisting of one or more horizontal planes fulcrumed at a point in advance of their centers, and means connected to their front ends operable from the car frame for manually holding the front ends of the said planes upwardly, for the purposes specified.

8. In an aeroplane, the combination with the poiser frame, means for sustaining the said frame in its flight, and the car frame pendent from the poiser frame; of means for guiding the direction of the poiser frame, comprising wings projected laterally from the poiser frame, consisting of a plurality of planes disposed in different horizontal planes successively one in advance of the other, said planes each being fulcrumed to tilt in their longitudinal direction, the fulcrums being in advance of their centers and means operable from the car frame connected to the front ends of the several planes and arranged for positively tilting and holding the wing planes with their front ends uppermost, as set forth.

9. In an aeroplane, a poiser frame, comprising a horizontally disposed casing closed at the front, sides, top and bottom, but open at their rear, the top having an opening, a drum located in the casing open at the rear and in line with the top opening, a rotary blower mounted in the casing in line with the top opening, a motor mechanism suspended on the poiser frame for actuating the blower, the top of the poiser frame having a rearwardly expanded flexible portion, the sides of said frame extending beyond the discharge or open end of the casing aforesaid, for the purposes specified.

10. In an aeroplane, in combination, a poiser frame having a horizontally disposed casing in its under side at the forward end, said frame from the casing rearwardly being of increasing resiliency, the casing being open at the rear whereby to discharge beneath the under side of the resilient portion of the poiser frame, the casing being divided into two compartments of substantially semi-circular shape, each of the said compartments having an axial opening in the top, a centrifugal air propeller mounted in each compartment, a car frame pendent from the poiser frame, a motor on such frame, and drive means that connect the

motor with the propellers for driving said propellers toward each other for the purposes specified.

11. An air ship, comprising a poiser frame, having a pair of transversely disposed openings, a car suspended therefrom, a motor on the car, horizontally disposed centrifugal blowers located in the poiser frame, geared with the motor, and auxiliary poiser frames or wings projected from the main poiser frame, each consisting of one or more

planes mounted to tilt in the longitudinal plane and fulcrumed so their rear ends normally hang down and means connected to the front ends of the several wing planes 15 operable from the car for holding the front ends of said planes swung upwardly, as set forth.
